Inventor

United States Patent Office.

RUSSEL FRISBIE, OF CROMWELL, CONNECTICUT, ASSIGNOR TO J. AND E. STEVENS & CO., OF SAME PLACE.

Letters Patent No. 73,966, dated February 4, 1868.

TOY-GUN.

The Schedule referred to in these Letters Patent and making part of the same.

TO ALL WHOM IT MAY CONCERN:

Be it known that I, RUSSEL FRISBIE, of Cromwell, county of Middlesex, and State of Connecticut, have invented certain new and useful Improvement in Toy-Gun; and to enable others skilled to make and use the same, I will proceed to describe, by referring to the drawing, in which the same letters indicate like parts in each of the figures.

The nature of this invention will be understood from the specification and drawing.

The handle A is made in one piece of metal, as shown back of the point or depression a, which is clearly shown in the drawings. The front or barrel portion of this gun is made in two halves, one half of which is made in the same piece of metal with the handle A. This part or barrel portion is provided with a hub, c, upon which the trigger B is mounted. It is also provided with a hub, d, near the front end, and hub d' near the back end, which (the hub d) forms the breech of the barrel, C, and also for a nut to receive fastening-screws, by means of which the two parts and all the mechanism are held in their proper working position inside of the barrel and spring-case d''. Directly over this barrel C is provided a nipple, e, or cup e', for holding fulminate preparation, in the form of a cap or vegetable disk, to be exploded by percussion. Each half of the case d'' has a depression, which serves for bearings for the clutch-hub D.

E is a spring. The peculiarity of this spring consists in its mode of construction, relatively to the mode of securing it in its place, and its action upon the hammer or actuating-rod F, the shape of which is clearly shown in the drawings. The prong h of this spring rests against the shoulder i of the spring-case, while the prong i' takes its bearing in the slit of the clutch-hub D. One end of this clutch-hub D is provided with a slit, H, and dog I. The office of this slit H is to receive the prong i' of the spring E. The dog I is to hold the spring in its proper place, and from undue friction upon the actuating-rod F. Each end of this clutch-hub takes bearing in the depressions formed in the spring-case d''. J is a pebble or torpedo-receptacle secured to the outer end of the arm F. This rod F is provided with a nipple, e, or cup e', the office of which is to receive, or to explode, fulminate preparation, in the form of caps or vegetable disks, by means of the combined action of the spring E and arm F, placed near the outer end of the barrel C, or in or upon the nipple e or cup e'.

The upper end L of the trigger B is made slightly wedging or spiralling, so that when the arm or rod F is pressed back into the notch n, by simply pulling said trigger in the usual way, said wedge or spiral formation L will disengage the rod F from the notch n, and allow the receptacle J, nipple e, or cup e' to move rapidly forward by the accelerating force of the spring E. P is a striking-pad, the face of which is formed slightly diverging from a straight line from the centre of the hub D, the object of which formation is to ease off the percussion of the rod F as it strikes against the diverging face of the pad P.

In describing this my invention, I have endeavored to show, at the same time, the nature and advantage thereof, so as to enable others skilled to make and use therefrom.

I claim the spring E, with the clutch-hub D, rod F, pebble-socket J, trigger B, substantially as and for the purpose described.

RUSSEL FRISBIE. [L. S.]
